UNITED STATES PATENT OFFICE

2,035,168

INTERMITTENT GRIP DEVICE

Adolf Kregling, Stratford, Conn.

Application May 21, 1934, Serial No. 726,689

3 Claims. (Cl. 74—164)

The present invention relates to improvements in merry-go-rounds, particularly of the type in which one or more of the occupants provide the propelling power, and which provides amusement, recreation and healthful exercise for children as well as adults, the movements employed in propelling the merry-go-round being similar to those used in rowing a boat. It may be used in the home either indoors or out, and 10 at playgrounds, beaches, etc.

An object is to provide a merry-go-round structure of simple, and sturdy construction, and so balanced that great force will not be required to operate it, permitting a single child to propel 15 it while several others are riding on it. Another object is to provide improved propelling means in which there are no dead centers, as in the case where cranks are used, and in which no portion of the stroke of the operating hand lever is 20 wasted, as is the case with structures employing ratchets. It is further proposed to provide a merry-go-round that can be started from any standing position by one or more of the occupants, as at the very moment any one of the occupants 25 pulls on one of the hand levers the frame will begin to rotate. The operator may use the full stroke of the lever or may just nibble along with short movements of the lever, but every pull, long or short, will apply rotative power. A further object is to provide a drive means which 30 will permit any one or more of the operators to stop pulling and rest any time he or they may desire, while other operators apply power from other seats. It is also proposed to provide 35 drive means which will permit the frame to coast from its own momentum, and during such coasting the hand levers will remain stationary at any position in which they may be held, so that the danger of injury from swinging levers is 40 eliminated.

Another object is to provide safety means which automatically disengages the hand levers in the event that the merry-go-round is turned backward, so that there is no danger of breaking 45 or jamming the mechanism.

With the above and other objects in view, embodiments of the invention are shown in the accompanying drawings and these embodiments will be hereinafter more fully described with 50 reference thereto, and the invention will be finally pointed out in the claims.

In the drawings:

Fig. 1 is a perspective view of a merry-go-round, according to the exemplary illustrated embodiment of my invention.

Fig. 2 is a view partially in side elevation and partially in vertical section, and with parts broken away.

Fig. 3 is a side elevation of one of the propelling units.

Fig. 4 is a rear elevation thereof.

Fig. 5 is a vertical sectional view thereof.

Fig. 6 is a side elevation showing in full lines the position in which the safety means becomes operative, and showing in dot-and-dash lines 10 an intermediate position as the lever is being pulled in propelling direction.

Fig. 7 is a side elevation of a modified form of propelling unit.

Fig. 8 is a rear elevation thereof.

Similar reference characters indicate corresponding parts throughout the several figures of the drawings.

Referring to the drawings the merry-go-round, according to the exemplary illustrated embodiment of my invention, comprises a pedestal or base 10, having a socket 11 therein in which a stationary post 12 is secured and supported at its lower end. The pedestal may be bolted or otherwise secured to the floor, or when used out of doors may have channel iron extensions 13 secured to its feet 14 to provide a relatively wide balanced support for the structure. A stationary bevel gear 15 is secured upon the post 12.

A rotary hub 16 having a bearing bushing 17 at its lower end is rotatably mounted on the shaft 12 and rests on a ball bearing unit 18 supported on the upper end of the pedestal 10 to provide vertical support. A plurality of bevel pinions 19 (four in the illustrated structure) are mounted in the hub and mesh with the stationary bevel gear 15, their shafts 20 being journaled in radially disposed hub bearings 21 formed in the side of the hub. The lower inside of the hub forms an oil reservoir in which the bevel pinions dip and carry oil up to be distributed to the stationary bevel gear and to the various hub bearings 21, ducts 22 being provided for this latter purpose which extend from the inner surface adjacent the bevel gears to the hub bearings. A duct 23 also extends to the bearing bushing 17. The gear and hub structure is practically self-lubricating, and is also fully enclosed against dirt and water. To this latter purpose a skirt 24 formed on the lower end of the hub 16 surrounds the ball-bearings 18, and a flanged cover 25 is secured to the upper end of the hub 16 by bolts 26.

Upon the upper side of the cover plate 25 a

series of block portions 27 having slots 28 are integrally formed, and to which the inner ends of the radially extending carrier bars 29 are secured by bolts 30, these bars being formed of

5 T-iron and having the upright portions engaged in the slots 28 while the horizontal top portions seat on the upper surfaces of the block portions. Obviously these carrier bars may be of any suitable form.

10 A sleeve member 31 is secured at its lower end by set screws 32 to the cover plate 25, and is provided at its upper end with a bearing bushing 33 engaging the upper end of the post 12 and with a head-piece 34 having a series of ears 35

15 cast thereon in which the upper ends of stay or guy rods 36 are secured, their lower ends being secured to brackets 37 provided near the outer ends of the carrier bars. The carrier bars are connected by tie pieces 38, preferably of angle iron. The frame thus formed is of rigid and steady construction, effectually braced, and supported in balanced rotatable relation about the stationary post 12.

20 Suitable bucket seats 39 having foot rests 40 are mounted upon the outer ends of the carrier bars 29. Obviously other seats may, if desired, be placed on the tie pieces 38 in alternate relation between the seats 39, and these latter can be in the form of horses or other animals, automobiles, or other such objects which would be attractive or appealing to children.

25 Driving or clutch shafts 41 are mounted beneath and in line with the carrier bars in bearings 42 secured to the carrier bars. A hand operated clutch, presently to be more fully described is mounted on the outer end of each shaft, while the inner end is connected by a flexible coupling 43 to the pinion shaft 20, in order to make alignment of the bearings easier, and to compensate 30 for any irregularities in the structure. A collar 44 secured on the shaft at the inner side of the bearings 42 prevents longitudinal displacement of the shaft.

35 The clutch comprises a driving collar 45, preferably of cast iron and fastened to the shaft 41 by a key 46. A clamping friction ring consisting of two half-sections 47 and 48, hinged together at 49, fits about the periphery of the driving collar 45, the half-sections being preferably 40 lined with a friction metal 50 to more effectually grip the collar. The clamping ring may, if desired, be in the form of a one-piece split ring. A cradle 51 has bearings 52-52 at each side which fit the shaft 41 at each side of the driving collar 45. The sides of the cradle are connected at the upper and lower ends by transverse bridge portions 53 and 54, the portion 53 having an adjustable bearing screw 55 therein which bears against a lug 56 formed on the end 60 of the clamping ring section 47, an opposed lug 57 being formed on the end of the section 48, and having a stud 58 of hardened metal screwed therein.

65 The hand lever 59 is mounted upon a cross shaft 60 secured in the lower end of the cradle, and is provided with an eccentrically shaped cam part 61 disposed beneath the lug 57 in such relation that inward movement of the lever forces the lug 57 toward the lug 56 and tightly grips 70 the clamping ring about the driving collar 45 imparting rotation to the shaft 41 and the bevel pinion 19, the latter meshing with the stationary bevel gear 15 and causing the hub and frame to rotate about the stationary post. Movement of 75 the hand lever in the opposite direction causes

the clamping ring to instantly release, and so, moving the hand lever forward and backward causes rotation of the frame about the stationary post.

5 Forward movement of the hand lever with respect to the cradle is limited by means of a U-shaped bracket 62 secured at each side of the cradle. In order to overcome lost motion a coil spring 63 is provided between the lower end of the cradle and the lower end of the lever, the 10 ends of the spring being seated in a pocket 64 formed in the part 54 of the cradle and a pocket 65 in the end of the lever.

15 A bracket 66 is mounted on the bearing 42 and projects in line with the cradle, where it is 15 provided with an adjustable safety release or stop screw 67 disposed in the path of the cam part 61 and adapted to contact it when the hand lever is swung to the limit of its forward movement, as shown in full lines in Fig. 6, causing 20 the cam part to be pressed into releasing relation with respect to the clamping ring. If, by chance, the merry-go-round is pushed backwards while an operator is holding on to the hand lever, causing a reverse rotation of the shaft 41 and 25 collar 45, the cam part coming into contact with the safety release screw 67 automatically disengages the friction clamping ring from the driving collar. The merry-go-round may be pushed forward or backward at any speed without danger 30 of jamming or breaking the working mechanism. Another point of advantage is that the hand lever remains stationary at all times, except when the operators apply power.

35 In Figs. 7 and 8 I have illustrated a modified form of clutch unit. A hardened driving collar 68 is secured to the shaft 41 by means of a key 69, and is engaged by a bevel-surfaced shoe 70 provided on the end of the hand lever 71, the latter being pivotally mounted at 72 in a cradle 73 40 having bearing hubs 74-74 at each side rotatably engaged in the shaft 41 at each side of the collar 68. A plunger 75 disposed in a tubular extension 76 of the cradle is pressed into engagement with the shoe 70 by a spring 77 to take up 45 lost motion. A safety stop and release screw 78 is adjustably mounted in a bracket extension 79 of the bearing 42 and is disposed in the path of the shoe 70 to automatically release it when the shaft is rotated backwards, acting in a similar 50 manner to the release screw 67 of the first embodiment.

55 The operation is substantially the same as in the first embodiment, the forward or push movement of the lever and cradle being free of the driving collar and the rearward or pulling movement gripping the collar and rotating it.

I have illustrated and described preferred and satisfactory embodiments of the invention, but it will be obvious that changes may be made 60 therein, within the spirit and scope thereof, as defined in the appended claims.

Having thus described my invention what I claim and desire to secure by Letters Patent is:—

1. In a driving mechanism for a driving shaft 65 having a cylindrical portion, a fixed journal bearing for said shaft, a cradle member pivotally mounted on said shaft at one side of said bearing, clamping means surrounding said cylindrical portion of said shaft having a pair of projected 70 oppositely disposed spaced ends adapted upon being pressed toward each other to cause said clamping means to grip said shaft, an abutment carried by said cradle member engaging one of said projected ends, a lever pivotally mounted in 75

said cradle member about an axis removed from the axis of said shaft and adapted to be moved to and fro in gripping and releasing directions, means on said cradle arranged to limit movement 5 in releasing direction with respect to said cradle and an eccentric cam portion carried by said lever engaging said other projected end, and adapted upon movement of said lever in gripping direction to press said other projected end toward 10 said first projected end, and upon movement in releasing direction to permit movement of said other projected end away from said first projected end, and stop means carried by said fixed journal bearing adapted at a predetermined position 15 of said cradle member to engage said lever to press it in releasing direction.

2. In a driving mechanism for a driving shaft having a cylindrical portion, a fixed journal bearing for said shaft, a cradle member pivotally mounted on said shaft at one side of said bearing, clamping means surrounding said cylindrical portion of said shaft having a pair of projected oppositely disposed spaced ends adapted upon being pressed toward each other to cause said 25 clamping means to grip said shaft, an abutment carried by said cradle member engaging one of said projected ends, a lever pivotally mounted in said cradle member about an axis removed from the axis of said shaft and adapted to be moved to and fro in gripping and releasing directions, means on said cradle arranged to limit pivotal movement in releasing directions with 30 respect to said cradle, an eccentric cam portion carried by said lever engaging said other projected end and adapted upon movement of said

lever in gripping direction to press said other projected end toward said first projected end, and upon movement in releasing direction to permit movement of said other projected end away from said first projected end, spring means acting 5 between said cradle member and said lever normally pressing said lever in gripping direction, and stop means carried by said fixed journal bearing adapted at a predetermined position of said cradle to engage said lever to press it in releasing direction. 10

3. In a driving mechanism for a driving shaft having a cylindrical portion, a fixed journal bearing for said shaft, a cradle member pivotally mounted on said shaft, a lever pivotally mounted 15 in said cradle member about an axis removed from the axis of said shaft and adapted to be moved to and fro in gripping and releasing directions, means on said cradle arranged to limit pivotal movement in releasing direction with respect to 20 said cradle, and clutch means cooperating between said lever and said cylindrical portion of said shaft adapted to frictionally grip said shaft in the gripping direction of movement of said lever relative to said cradle and to be released 25 from said shaft in the releasing direction of movement, movement of said lever adapted to move said cradle about the axis of said shaft, and spring means normally pressing said clutch means in gripping direction, and stop means carried by said 30 fixed journal bearing adapted at a predetermined position of said cradle to engage said lever to press it in releasing direction.

ADOLF KREGLING.
